LIGHTING DEVICE

Warren W. Sackett, Milwaukee, Wis., assignor to
 Milwaukee Gas Specialty Company, Milwaukee,
 Wis., a corporation of Wisconsin

Application November 20, 1931, Serial No. 576,251

7 Claims. (Cl. 158—115)

My invention relates to igniters for gas burners and has particular relation to an igniter for igniting a heater burner from a pilot burner.

I have considered the problem of igniting gaseous fuel as used in ovens, heaters, stoves and the like, and have observed that the devices of the prior art are not always satisfactory for the reason that they are not positive in operation, inasmuch as at times the igniting gas burns so rapidly as to prevent ignition of the gas issuing from the burner to be ignited.

It has also been observed that in most failures of this type, the failure to ignite the burner properly permits gas to escape from the oven burner and the accumulation of the escaping gas mixing with the surrounding air forms a combustible and highly explosive mixture which may be ignited by an adjacent pilot flame or otherwise and result in a serious explosion. A large accumulation of gas of this type is also dangerous due to the fact that the gas possesses a highly toxic value and is dangerous to persons in the immediate vicinity.

It is thus necessary, in devices of prior types, for the operator to maintain a close observance of the appliance each and every time the gas is turned on and the ignition device is operated. It is thus seen that in this type of device the operation is dependent upon the skill and carefulness of the operator.

The present invention therefore contemplates providing an ignition device which is reliable and positive in operation, and which is of simple construction so that it may be operated easily and safely.

My ignition device may be used or modified for use in connection with any type of lighter, such as the "flash" type of igniter or the "gravity" type of lighter. The device is simple, reliable, sturdy and inexpensive.

Other and further features and objects of the invention will be more apparent to those skilled in the art upon a consideration of the accompanying drawing and following specification, wherein is disclosed a single exemplary embodiment of the invention with the understanding, however, that such changes may be made therein as fall within the scope of the appended claims without departing from the spirit of the invention.

In said drawing:

Figure 1 is a plan view of my ignition device as applied to the burners of a stove and an oven or like devices in side by side relation;

Figure 2 is a view partly in section and partly

in elevation of my lighter device as applied to a "gravity" type of lighter;

Figure 3 is a view partly in elevation and partly in section of my improved lighting device as applied to a "flash" type of lighter. The view is taken substantially along the line 3—3 of Figure 1, and

Figure 4 is a detail perspective view showing the relationship between the end of the lighter tube and the pilot tip.

The present invention deals particularly with an ignition system in which the flame from a pilot light is conducted to the heater burner when ignition of the gas issuing from the heater burner is desired. In the embodiment of the invention shown and described the igniter is used for igniting the gas issuing from the burner of an oven heater or the like which is usually situated in side by side relation with the top burners of a stove, but it is apparent, however, that the device may be used or modified for use with other arrangements of burners, types of burners and ignition systems and for igniting other kinds of fuel.

Referring now to the drawing for a more complete disclosure of the invention, there is shown at 10 a gaseous fuel manifold of the usual construction. The manifold is connected to the stove burners 11 by means of supply pipes 12 and the flow of gas through the supply pipes into the burners 11 is controlled by means of valves and mixing chambers (not shown) of the usual construction.

In the embodiment of the invention shown in Figures 1 and 3, the igniter is shown in connection with a "flash" type of igniter used for igniting the stove burners. The igniter system includes a lighter tube 13 which is connected with the manifold 10 by means of a valve 14 of the push button type which is set to deliver a small quantity of gas to the pilot light so long as the plunger button of the valve is not depressed. If only this minimum amount of gas is supplied the gas issues from the upper ports 16 and from the lower ports 16' of a pilot burner 17 in such volume that the gas burns in a small flame 18. If the plunger of the valve 14 is depressed, however, a larger volume of gas under greater pressure is supplied to the pilot burner 17 and the gas issuing from the upper ports 16 burns in a long flash of flame 19 of sufficient length to reach the ports of the burners 11. Gas also issues in increased volume from the lower ports 16'. If any of the valves controlling the flow of gas in the pipes 12 are opened, the gas issuing from the cor-

responding burner or burners 11 will be ignited by the flash from the pilot flame.

Supplementary ports 20 are provided in burner 17 for relay purposes to support the main flame 19 when the rate of flame propagation is less than the rate of flow of the gas from the ports 16.

The pilot flame is preferably protected from drafts and the like by means of a cup-shaped base 21 over which a cup-shaped or cylindrical hood 22 is telescoped to form an inclosure. The base 21 is provided with openings 23 therein to permit the entrance of air to the hood to support combustion of the pilot flame and another opening 24 is provided in the top of the hood 22 to permit the products of combustion to escape from the hood. Other openings 26 are provided in the side wall of the hood to permit the "flash" flame to reach the burners 11.

Still another opening 27 is provided in the side wall of the hood in order that a pipe, lighter or conduit tube 28 may be inserted through the opening. The inner end of the pipe 28 preferably covers one or more of the lower ports 16 in the pilot burner 17 and is provided with a hollow annular channel-shaped lug 29 adapted to encircle the pilot burner 17 and act as a support for the inner end of the pipe 28, as shown in Figure 4. The outer end of the pipe 28 passes through an enlarged opening in the wall 31 of the oven and ends in a position adjacent the ports 32 of the oven burner 33. The tube 28 is preferably provided with a narrow slot 34 along its upper portion to permit the escape of gas from the tube in a long, narrow stream which, when ignited, forms a ribbon of flame connecting the pilot burner and the heater burner. Gas for the tube 28 is supplied, in this embodiment of the invention, from the ports 16 in the pilot burner.

Gas is supplied to the oven burner 33 through a valve 36, which is adapted to regulate the flow of gas to the burner, and a mixing chamber 37 for mixing the gas with air to improve combustion of the gas, both of which devices are of the usual construction.

In operation of the device shown in Figures 1 and 3, gas is admitted to the pilot tube 13 and the pilot burner 17 by means of the valve 14, and the gas issuing from the pilot burner is ignited to form a flame 18 which is kept burning continuously, as long as gas is supplied to the manifold 10. If one of the stove burners 11 is to be lighted, the valve controlling the flow of gas through the pipes 12 to the proper burner 11 is turned on. As soon as gas is issuing from the ports of the burner 11, the button of the valve 14 controlling the flow of gas within the lighter tube 13 is depressed and a greatly increased flow of gas results. This increased flow of gas results in flames 19 at each of the ports of the pilot burner which are of sufficient length to reach the burners 11 and to ignite the gas issuing from any or all of the burners.

Since the pipe 28 covers one or more of the ports 16 in the pilot burner, gas issues through the ports in sufficient quantities to fill the tube 28. The end of the tube adjacent the pilot flame is closed except for the opening 34 along the top of the tube, and therefore the gas within the tube is not ignited. The gas issues through the slot at the upper part of the tube in a long, narrow ribbon which is ignited by the pilot flame 18 to burn in a ribbon of flame 38 along the top of the tube. The gas which does not issue through the slot 34 passes out the outer end of the tube adjacent the burner 33 to form an elongated flame 39 which

is quite suitable for igniting the gas issuing from the ports 32 in the burner when gas is admitted to the burner through the valve 36 and mixing chamber 37.

As soon as the gas issuing from the ports 32 has been ignited, the button 14 is released to decrease the flow of gas in the tube 13 and, since the pressure of the gas issuing from the ports 16 is not great enough to cause the gas to fill the tube 28, the flame 34 dies out.

In the embodiment of the invention shown in Figure 2, the top burners may be ignited in the same manner as when the "gravity" type of lighter is used, that is, the plunger of the "flash" control valve, such as the valve 14, need not be depressed or otherwise operated. Gas is admitted to the pilot burner 17 in sufficient quantity to maintain an even low flame. Each of the tubes 28a and 28b is provided with a suitable lug 29a, which encircles the pilot burner 17 and which is engaged in a suitable depending cylindrical flue member 40 projecting from the opening 24 in the housing or hood 22. The tubes project through suitable openings 26a formed in the hood 22, toward the respective burners, the tube 28a projecting toward the oven burner. The hood 22 has a cutout portion 27 immediately above the entrance of the tube 28a and the tube is slotted to provide a passage for the flame from the ports 16 through opening 27 and along the upper slotted surface of the tube 28a to the burner 33.

Referring in more detail to the tube 28a, this tube is inclined downwardly from the pilot burner to the heater burner 33, and an extending portion 41 of the tube 28a rests over the upper periphery of the burner 33 to support the outer end of the tube. The tube is provided on its lower side with an opening 42 adjacent the ports 32 of the burner.

If desired, the top burners 11 may be provided with the "gravity" type of ignition and may be provided with tubes 28b projecting through suitable openings 26a in the hood 22 in the same manner as described in connection with tube 28a. These tubes project to the respective top burners and are suitably secured thereon so that when it is desired to ignite the burners gas issuing from the ports of the burners will travel through the tubes 28b to the igniter 17 and will then travel back as a flame along the upper slotted surface of the tubes to the burners to ignite them. This igniting operation is much the same as that used in igniting the oven burner 33.

In the operation of this latter device, gas is furnished to the pilot burner 17 by means of a tube 13 and the pilot flame 18a is ignited as before. If it is desired to operate the heater 33, gas is admitted to the heater through the valve 36 and mixing chamber 37. The gas passes out of the openings 32 in the heater 33, rises upwardly through the opening 42 of the tube 28a, into the tube and is carried upwardly and inwardly through the tube to the inner end thereof, where the gas issuing from the end of the tube is ignited by the flame 18a. The gas issuing through the slot 34 of the tube is ignited to form a long ribbon of flame 38a which in turn ignites gas flowing from the port 32 in the heater 33, thus igniting all of the gas issuing from the heater.

It is apparent that because the gas in the tube 28 is not mixed with air to any great extent, combustion within the tube will not occur. The

gas issues through the slot 34 in a narrow stream, and since the gas has not been mixed with air, rapid ignition does not occur and the gas burns with a steady flame well adapted for igniting the gas issuing from the heater burner. The device is simple, reliable and inexpensive.

Although I have described specific embodiments of my invention, it is apparent that modifications may be made by those skilled in the art. These modifications may be made without departing from the spirit and scope of the invention as set forth in the appended claims.

I claim as my invention:

1. In a burner ignition system, a pilot burner having a plurality of ports, one of which is utilized to provide gas for a pilot flame, a heater burner, a lighter for conducting flame from the pilot burner to the heater burner comprising a tube having an opening along its upper side, and means for introducing gas under increased pressure through said pilot burner to said tube for ignition by said pilot flame when ignition of the heater burner is desired.

2. In a burner ignition system, a pilot burner flame, a heater burner, a lighter for conducting flame from the pilot burner to the heater burner comprising a tube extending over a port of the pilot burner, and means for introducing gas under increased pressure into the pilot burner whereby the tube is filled with gas which escapes through the opening in the tube and is ignited by the pilot flame to conduct the flame to the heater burner when ignition of the heater burner is desired.

3. In a burner ignition system, a pilot burner having fuel supply means, a heater burner, a lighter for conducting flame from the pilot burner to the heater burner comprising a conduit having a longitudinal opening at the upper side thereof, and means controlling said pilot burner fuel supply means for filling the conduit with gas under increased pressure when ignition of the heater burner is desired.

4. In a domestic gas range having an oven burner and a plurality of top burners, a burner ignition system comprising a pilot burner having a plurality of ports, one of which is utilized to provide gas for a pilot flame, means for supplying fuel to said pilot burner, a heater burner, a lighter for conducting flame from the pilot burner to the heater burner comprising a tube having an

opening along its upper side, and means controlling said fuel supply means for filling the tube with gas under increased pressure when ignition of the heater burner is desired.

5. In an ignition system including a plurality of gas burners and an oven burner removed therefrom, said system having a flash igniter disposed centrally of said gas burners, the combination with said flash igniter of a conduit leading from said igniter to a point adjacent said oven burner, said conduit having a longitudinal slot in the top thereof, and means for introducing gas under pressure through said igniter into said conduit, said gas being ignited by said igniter and passing along said slot to said oven burner to ignite the same.

6. In combination, a pilot burner comprising a torch head having laterally extending ports, a hood over said torch head having openings in alignment with said ports, means for supplying fuel to said torch head, a conduit supported in one of said hood openings and enclosing one of said ports, said conduit having a longitudinally extending slot in the top thereof, an oven wall, an oven burner disposed on the side of said wall away from said pilot burner, said conduit extending through and being supported by said wall and terminating at a point adjacent said oven burner, and means controlling said fuel supply means for projecting lighting flames radially outwardly from said ports through said hood openings and for introducing fuel into said conduit, said fuel being ignited along said slot to provide for ignition of said oven burner.

7. In combination, a plurality of gas burners, an oven burner removed therefrom, a flash igniter disposed centrally of said gas burners and having vertically spaced port means, means comprising a slotted tube enclosing one of the lower of said port means for forming a relatively restricted gas and air admixture path to said oven burner, means for introducing gas under increased pressure into said igniter to project lighting flames from said igniter toward said gas burners, said last named means providing for flow of a stream of relatively free gas through said tube toward said oven burner, said gas being ignited along the slot in said tube by the flame from an upper one of said port means.

WARREN W. SACKETT. 50
